THOMAS A. McFARLAND, OF MEADVILLE, PENNSYLVANIA.

Letters Patent No. 64,891, dated May 21, 1867.

IMPROVEMENT IN CAN-OPENER.

The Schedule referred to in these Letters Patent and making part of the same.

TO ALL WHOM IT MAY CONCERN:

Be it known that I, THOMAS A. McFARLAND, of Meadville, in the county of Crawford, and State of Pennsylvania, have invented a new and useful Implement for Opening Oyster, Fruit, and other Cans, of which the following is a full, clear, and exact description, reference being had to the accompanying drawing, which makes part of this specification, and which represents a view in perspective of my improved can-opener.

It is the object of my invention to provide a cheap, simple, and effective implement for cutting an opening in a can by a single blow; and to this end my improvement consists in combining in a socket a series of curved pointed teeth, so arranged that when first forcing their way into the can their points shall be in contact with it and thus diminish the resistance to be overcome, and, consequently, the amount of force to be expended; but as the cutting continues, the cutting edges expand until they meet those of the adjacent cutter, and thus punch out a piece of the form circumscribed by the teeth.

To carry out the object of my invention I provide, (as shown in the drawing,) a suitable handle, A, having a head or stock, B, of a diameter corresponding to that of the cutter. Upon this head I turn a shoulder, a, to receive a series of tooth-shaped cutters, C, curved to fit the handle, and fastened by screws or other suitable means. I also bevel the teeth on their inner edges, but leave them flush on their outer sides. It will be seen that the cutters touch each other at their bases, but that their points are some distance apart. The cutters, it is obvious, might be formed either of a single piece or of sections, separately secured to the handle. The cans to which my invention is applicable are made of sheet tin or some similar material.

In operation the tool is placed on the head of the can, and the points of the teeth driven in by a smart blow, and the cutters forced down until their forks or bases have cut through the can, when a piece will have been cut out of the form of the cutters. The teeth being bevelled on the inside tend to compress the plug removed, and cause it to remain inside the cutter, thus facilitating its removal from the can. A single blow will generally be sufficient to cut the opening.

I am aware that it has been proposed to open cans by the use of a single cutter operating like the single blade of a shear, that is, requiring several cuts or blows to remove the plug. I am also aware that cutters have been used in combination with separate spring handles sliding through a ring, and thus compressing the cutters to cut a tapering plug out of cork or other soft substance.

I, therefore, do not claim broadly cutting an opening in a can, but—

Having thus fully described my improvement, what I claim therein as new, and desire to secure by Letters Patent, is—

As a new article of manufacture, the can-opener consisting of the handle A and cutters C, constructed, arranged, and operating as described for the purpose of cutting out a disk or plug at a single blow, as set forth.

T. A. McFARLAND.
